WASTE TRAP

Filed Jan. 21, 1924

Inventor
Albert S. Newton
By Horatio E. Bellows
Attorney

UNITED STATES PATENT OFFICE.

ALBERT S. NEWTON, OF PROVIDENCE, RHODE ISLAND.

WASTE TRAP.

Application filed January 21, 1924. Serial No. 637,434.

To all whom it may concern:

Be it known that I, ALBERT S. NEWTON, a citizen of the United States, residing at Providence, in the county of Providence 5 and State of Rhode Island, have invented certain new and useful Improvements in Waste Traps, of which the following is a specification.

My invention relates to waste traps and 10 has for its essential objects to provide a waste trap having provision for baffling the incoming water to throw it back with the result that the water in the seal is increased so as to afford a deep seal in the trap. A 15 few inches increase in the depth of the water constituting the seal means an increase of several weeks in the length of time before the water is evaporated.

Another object is to provide for ready accessibility to the trap body interior, combined with the means for automatically preventing back pressure and siphonage.

Another object is to adapt the automatic baffling means to bodies of various shapes, 25 and also to prevent displacement of the baffle plate after its removal from the trap body.

A further object is to attain these ends in a strong, simple and inexpensive structure.

To the enumerated ends primarily my invention 30 consists in such parts and in such combinations of parts as fall within the scope of the appended claims.

In the accompanying drawings which 35 form a part of this specification,

Figure 1 is a central vertical section of a trap embodying my invention,

Figure 2, a section of the same on line 2-2 of Figure 1, and

Figures 3 and 4, vertical central sections 40 of modified forms of my invention.

Like reference characters indicate like parts throughout the views.

In the form of my invention shown in Figures 1 and 2, a substantially cylindrical trap body 6 has intermediate its length an internal annular flange 8 dividing the interior into upper and lower chambers 10 and 11 communicating with each other through a central opening 12. Opening into 45 the trap near its bottom is a pipe 15 affording a water inlet 16 into the lower portion of the chamber 11. A pipe 18 in the upper portion of the body affords an outlet opening 19 from the upper portion of the chamber 10. In the top of the body is an opening 22 with a thread 23 engaging a thread 50

24 on a flange 25 inset from the periphery of a plate 27 constituting a removable cover for closing the opening 22. A polygonal projection 29 accommodates a wrench. Fast 60 in a threaded socket 30 in the cover is a depending or vertical tubular post 32 in which is slidably mounted a rod 33 in which is fixed a laterally projecting pin 35 extending loosely into a longitudinal slot 36 in an intermediate portion of the post. Fixed to the lower end of the rod 33 is a downwardly directed convexo concave baffle plate 38. This plate normally rests by gravity upon the flange 8, thus covering the opening. 70 The movement of the water is from the inlet pipe upwardly through the body and the outlet pipe, impeded by the flange 8, and by the baffle plate 38 which rises under pressure to a position against the post 32 shown in broken lines in Figure 1. After passage of the water as described the baffle plate by gravity returns into contact with the flange and prevents back pressure. The location 75 of the cover in the top of the trap affords accessibility to the trap from above making it possible to utilize the trap in a bath room floor adjacent the bath tub. In removing the cover 27 from the trap the rod 33 is prevented from accidental escape by the contact of the pin 35 with the post at the extremity of the slot 36.

In the modified form of my invention shown in Figure 3 the baffle plate 40 is upwardly directed, and cooperates with the edge of the flange 8, rather than with the face of the flange in effecting a closure. The cover 27 is herein located in an opening 41 in the bottom of the trap rather than in the top thereof. In this construction the outlet pipe 18 is located in the center of the top of the trap. The baffle plate normally rests upon the top of the post 32. The water under moderate pressure passes from the pipe 15 upwardly over the baffle plate 40, through the opening 12 and thence through the outlet pipe 18; but under increased force the water in its passage elevates the baffle plate to the position shown in broken lines, thus cutting off the flow and preventing siphonage.

In the modified form of my invention shown in Figure 4 the parts are as those shown in Figure 3 except that the post 32 extends into the chamber 10, and the baffle plate 40, of less diameter, engages the top 100 of the trap body at the mouth of the pipe 18

to close the passage 19 when the force of the water is increased.

I claim:—

1. In a waste trap, a body having upper and lower chambers, the latter constituting the seal chamber, said chambers being provided with outlet and inlet respectively, a seat intermediate said inlet and outlet, and a baffle interposed between said inlet and outlet and movably mounted for cooperation with said seat, said baffle constructed to retard the inflow of the water to maintain maximum water in the seal chamber, and to automatically prevent back pressure and siphonage.

2. In a waste trap, a body having inlet and outlet and upper and lower chambers, the latter constituting the seal chamber, said chambers being disposed upon opposite sides of a seat, and a baffle interposed between said inlet and outlet and movably mounted for cooperation with said seat, said baffle constructed to retard the inflow of the water to maintain maximum water in the seal chamber, and to automatically prevent back pressure and siphonage, said baffle having concave surface for the impact of the incoming water.

3. In a waste trap, a body having upper

and lower chambers, the latter constituting the seal chamber, said chambers being provided with outlet and inlet respectively, a seat intermediate said inlet and outlet, and a baffle interposed between said inlet and outlet and movably mounted for cooperation with said seat, said baffle constructed to retard the inflow of the water to maintain maximum water in the seal chamber and to automatically prevent back pressure and siphonage, said baffle having concave surface for the impact of the incoming water, and a guide for said baffle with means to prevent displacement of the latter.

4. In a waste trap, a body provided with an inlet, and an outlet, said body being provided with an opening spaced from the inlet and outlet, an annular seat in the body intermediate the inlet and outlet, a cover detachably mounted in the opening, a tubular post on the cover provided with a longitudinal slot, a rod slidably mounted in the post, a projection on the rod registering in the slot, and a baffle plate on the rod engageable with the seat.

In testimony whereof I have affixed my signature.

ALBERT S. NEWTON.
